UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

JOURNAL-BOX.

SPECIFICATION forming part of Letters Patent No. 718,585, dated January 13, 1903.

Application filed August 30, 1902. Serial No. 121,616. (No model.)

To all whom it may concern:

Be it known that I, JOHN W. STEPHENSON, of Toledo, Lucas county, Ohio, have invented a new and useful Journal-Box, of which the following is a full, clear, and exact description, reference being had to the accompanying drawings, forming part of this specification, in which—

Figure 1 is a vertical section of a journal-box with the lid applied thereto. Fig. 2 is a sectional plan view, the section being on the line II II of Fig. 1. Fig. 3 shows in vertical section, partly in side elevation, a journal-box embodying a modification of my invention. Fig. 4 is a vertical section on the line IV IV of Fig. 3. Fig. 5 is a perspective view of the adjustable seat for the lug on the box.

In the manufacture of journal-boxes of railway-cars difficulty has been experienced because of distortion of position of the lugs, caused either in the casting of the box or in the case of malleable iron boxes in its subsequent annealing. In some boxes the lugs will be nearer or farther from the front of the box than they should be or a little off the central line of the box, and in the effort to remedy this by hammering the lugs into position many lugs are broken or weakened and great loss results therefrom. Furthermore, it is often impossible to correct wholly the distortion of the lug, and when it is not corrected the lid will not fit the box accurately, and the purpose of the lid in excluding dirt, &c., is thus defeated. These and other difficulties are obviated by my invention, which I will now describe.

In the drawings, 2 is the box, 3 is the lug, and 4 is the pivot-pin hole for the lid 5. The lug is cast in a separate piece and is held by a central rivet 6 to a lug-seat 7, held to the box between two ribs 8 8, with dovetailed inner sides, and secured, preferably, by driving down a portion 9 of the metal into a notch or recess in the lug-seats 7 or into a recess in the box's surface. The lug has a circular portion 10', which fits in a circular recess 10 on the lug-seat, so that when the lug is riveted thereto it has a swiveling motion

which enables the lug to be turned and adjusted to suit any irregularities in the angle 50 of the face of the box or of the lug itself. This is a useful and important construction. The lug-seat 7 may be applied to the box in the same manner as that described with reference to Figs. 3, 4, and 5. 55

In Figs. 3, 4, and 5 I show a modification in which I employ an adjustable lug-seat 7', which is fitted to the top of the box between two ribs 11 11, with dovetailed inner sides, which extend longitudinally of the box, and 60 this adjustable seat has like ribs 8', which extend transversely thereto and are adapted to receive the base of the lug 3. The seat 7' is held in place preferably by upsetting the metal of one of the ribs 11 into a notch 12 in 65 the seat, and the lug is held to the seat preferably in like manner by upsetting the metal of the lug into a notch 13. I thus obtain a double adjustment of the parts, which enables me to get the lug exactly in the normal 70 position.

In a pending application, Serial No. 102,754, I claim a journal-box having a lug made separate from the box and secured thereto in desired position and a lid hinged to the lug and 75 also claim the same where the lug is secured in a dovetail socket in desired position.

Other modifications of my invention will be suggested to those skilled in the art, since

What I claim is—

1. A journal-box having a socket, a lug-seat adapted to be fitted to the socket in desired position, a lug adapted to fit on the seat in desired position, and a lid connected to said lug; substantially as described. 85

2. A journal-box, a lug made separate from the box, a swivel connection between the lug and the box, and a lid connected to said lug; substantially as described.

In testimony whereof I have hereunto set 90 my hand.

JOHN W. STEPHENSON.
